Fig. 2.

Fig. 3.

FIG. 1 is a perspective view of a cooking unit and stand combination showing my new design;

FIG. 2 is a fragmentary front elevational view thereof, and

FIG. 3 is an elevational view of the side thereof opposite that shown in FIG. 1.

FIG. 4 is a perspective view of a modified form of the cooking unit and stand combination shown in FIGS. 1, 2 and 3, it being understood that the front and undisclosed side thereof are substantially the same in appearance as the front and side of the combination disclosed in FIGS. 1 and 3 except for the controls on the front.

I claim:

The ornamental design for a cooking unit and stand combination, substantially as shown and described.
